QUICK-TRAVERSE MECHANISM FOR
WINDING MACHINESGlover C. Joyce, Worcester, Mass., assignor to
Whitin Machine Works, Whitinsville, Mass., a
corporation of MassachusettsOriginal application December 8, 1951, Serial No.
260,719. Divided and this application August
30, 1952, Serial No. 307,327

3 Claims. (Cl. 242—31)

1

This application is a division of prior application Serial No. 260,719, filed by me December 8, 1951, on Bobbin Winding Machine, and relates particularly to the quick-traverse mechanism therein shown and described.

It is the general object of the present invention to provide an improved construction of quick-traverse mechanism which can be operated at high speed with exceptional smoothness, and in which the direction of traverse is reversible without shock.

A further object is to provide a quick-traverse mechanism in which the loci of successive windings are slightly off-set axially to provide a locking or binding effect between successive windings. I also provide means for varying the length of traverse, while maintaining one end limit of the traversing swing unchanged.

The invention further relates to arrangements and combinations of parts which will be herein-after described and more particularly pointed out in the appended claims.

A preferred form of the invention is shown in the drawings, in which

Fig. 1 is a plan view of a quick-traverse mechanism embodying my invention;

Fig. 2 is a sectional side elevation, taken along the line 2—2 in Fig. 1;

Fig. 3 is a transverse sectional elevation, taken along the line 3—3 in Fig. 2;

Fig. 4 is a perspective view of an operating cam;

Fig. 5 is a development of said cam; and

Fig. 6 is a plan view of a guide-plate to be described.

The improved quick-traverse mechanism is shown as associated with a thread guide carriage C. The carriage C comprises a casing 150 having a tubular supporting member 151 which is slidable on a fixed shaft or supporting rod 50. The means for shifting the carriage C axially of the shaft 50 is fully described in the original application and forms no part of the present invention.

The casing 150 of the carriage C has a transversely extending bushing 153 (Fig. 3) having a hexagonal opening therethrough to receive a hexagonal and continuously rotated driving shaft 154.

A cam 155 (Figs. 3 and 4) having a double-throw peripheral cam groove 158 is secured on the bushing 153 and is thus rotated with the hexagonal shaft 154. A roll 156 is mounted on the lower end of a stud 157 (Fig. 2) and is received in the peripheral cam groove 158 of the cam 155.

2

The stud 157 is secured in one end of an arm 160 which is pivoted on a bushing 161 which is secured to a plate 162 (Fig. 6) by a binding screw 163 and nut 164. The plate 162 is fixed 5 in the carriage casing 150.

The upper end of the stud 157 is mounted for free angular movement in a bearing opening in a lever 166 having a thread guide G mounted in one end thereof.

10 The lever 166 has an elongated slot 168 to slidably receive a stud 169 which extends through a washer 170 (Fig. 3) and which is threaded in a nut 171 by which the stud 169 is clamped to the plate 162 in a selected position in a slot 172 (Fig. 6).

15 The stud 169 is preferably provided with a roll 169a (Fig. 2) which moves freely in the slot 168. The nut 171 is slotted off at opposite sides to fit the slot 172 and may be adjusted lengthwise of the slot but cannot rotate therein.

20 The stud 169 and roll 169a constitute a normally fixed pivot for the thread guide lever 166, but as the stud 169 is adjustable longitudinally in the slot 172, the stud 169 also comprises means 25 to vary the throw of the thread guide G.

As the slot 172 is aligned with the starting position of the thread guide G and lever 166, as shown in full lines in Fig. 1, the thread guide G will always return to the same end limit or starting position, regardless of the adjustment of the pivot stud 169. Consequently, all variations in length of throw of the thread guide take place at the opposite end of the stroke and at the limit toward the tip of the bobbin.

25 The cam groove 158 in the cam 155 is shown developed in Fig. 5, where it will be noted that the two rises of the cam groove 158 indicated at points 175 and 176 are at slightly different elevations. The effect of this is to slightly offset successive yarn windings axially relative to each other, so that an improved locking of the windings is thereby attained. The threads of each winding are laid between the threads in the next adjacent winding.

30 With the thread guide carriage and associated mechanism constructed as above described, the thread guide G can be very rapidly oscillated by the hexagonal driving shaft 154 in every longitudinal position of the carriage, and the throw of the thread guide G may be adjusted within wide limits by changing the setting of the stud 169. Furthermore, in every position of the stud 169, the starting position of the thread guide G will be at the full line position shown in Fig. 1.

35 45 50 55 Having thus described my invention and the

advantages thereof, I do not wish to be limited to the details herein disclosed, otherwise than as set forth in the claims, but what I claim is:

1. In a winding machine, a thread guide, a shiftable thread guide carriage, a thread guide lever mounted on said carriage, cam means to oscillate said thread guide lever in said carriage, means to vary the extent of the oscillation produced by said cam means, and additional cam means effective to maintain the starting point of every oscillation of said thread guide lever fixed and unchanged at one end of its traverse for all extents of oscillation.

2. The combination in a winding machine as set forth in claim 1, in which the means to vary the extent of oscillation of the thread guide lever includes a member adjustable along a guiding slot in a fixed plate, which slot is parallel to the center line of the thread guide lever in its predetermined starting position.

3. The combination in a winding machine as set forth in claim 1, in which the means to vary the extent of oscillation of the thread guide lever includes a member adjustable along a guiding slot in a fixed plate, which slot is parallel to the center line of the thread guide lever in its predetermined starting position, and in which said adjustable member comprises a stud extending freely through a longitudinal slot in the center line of the thread guide lever.

GLOVER C. JOYCE.
